UNITED STATES PATENT OFFICE

EDWARD C. ANGELL, OF NEW YORK, N. Y.

APPARATUS FOR MAKING PAPER CONTAINERS

Application filed March 25, 1929. Serial No. 349,767.

This invention relates to apparatus for forming paper containers, of the type comprising a body substantially tubular or conical, with a flanged bottom inserted into one end and secured by rolling or spinning the flange and the body end.

The object of the present invention is to provide a ledge or shoulder in the body near the end portion, to receive the edge of the body flange member as inserted and facilitates the rolling, or spinning of these two members. In the accompanying drawings showing one embodiment of my invention;

Fig. 1 is a horizontal section through the device.

Fig. 2 is a section enlarged through the part engaging the container.

Fig. 3 is a plan view partly in section showing further details of the apparatus.

Fig. 4 is a detail of operating mechanism for the forming device.

As shown in Figs. 1 and 2, the body portion of the container, here shown as conical, is placed in a holder 7 having a conical bore 8 corresponding to the body, and which body is shown as projecting beyond the end wall 9 of the holder by a portion 10, the holder being smaller than the body to permit its insertion in just this position.

A plunger 11 slides in guide blocks 12, 13, and a coil spring 14 pressed between a collar 15 on the plunger, and the block 12 will resist inward movement of the plunger.

At its forward end the plunger is secured to a head 16 of cylindrical shape whose outer end portion 17 may be slightly reduced, and which is of a diameter slightly greater than the opening or bore of the end wall 10 of the holder 7. A sleeve 18 slides at its bore on the head 16, with an apertured end wall 19 slidable on the plunger 12. A coil spring 20 is compressed between the sleeve end 19 and a collar 21 fast on the plunger 11. The latter will force the sleeve member outwardly on the head until pins 22 on the head, that slide in slots 23 in the sleeve, engage the inner ends of these slots, (see Fig. 1). The outer end portion of the

sleeve 18 has the bore enlarged, preferably

converging outwardly, to form an annular space or channel between the head and sleeve, as shown in Fig. 2.

This head and sleeve arrangement is of a size that when the plunger is advanced to engage the projecting end 10 of the body, see Fig. 1, this end will register with this annular space and will pass therein as the head and sleeve, now in the relative positions shown in Fig. 1, advance. Since the sleeve normally projects beyond the head, the sleeve will inclose the end portion 10 of the body, and the plunger is advanced to bring the sleeve end wall against the end wall 9 of the holder as shown in Fig. 2, that will arrest the sleeve. But the continued advance of the plunger will carry the head 16 forward from its normal position inside of the sleeve as in Fig. 1, and the head will pass inside of the body projecting end 10, that is 55 60 65 70 75 80 85 90 95 100 conical. The end of the head is the same size as the extremity of the conical body, and as the head will now advance through the arrested sleeve by advance of the plunger, permitted by compression of spring 20, the cylindrical head will move into the conical body end, that is of decreased diameter. And therefore the body end portion must expand, permitted by the annular space between the head and the bore of the sleeve. Continued advance of the head through the sleeve will take place until the head presses the body, now expanded against the end wall 9, whose bore is slightly smaller than the head. This will result in a ledge or shoulder being formed between the outer portion of the head at the end, and the wall 9 of the holder, as clearly shown in Fig. 2. And it will be further seen that beyond this shoulder the body portion is now substantially cylindrical. This will better adapt the body to receive the end member, in the form of a flanged cup, that is inserted into this expanded end of the body, until the body disc portion engages this shoulder.

The general operation of the machine is indicated in Fig. 3, where the bodies are formed at 30 and fed into the holders 7 that are carried on an endless chain. At an advanced station 31 the flanged cap member

is inserted in the body in the holder; and at a further advance station 32 the body and the flanged bottom are rolled together by a spinning operation. The present invention 5 is applied at the station 33 before the holders reach the station 31 to receive the bottom, and here the body is treated to form the shoulder and enlarged end portion, by the mechanism shown in Fig. 1 and the 10 several devices are driven from a main shaft 34 and a cam 35 on this shaft engages the roller 36 on the end of the plunger 11, with a slotted guide 37 that straddles the shaft 34, the spring 14 pressing the plunger 15 roller against the cam.

A machine of this character is shown in the patent to Stanley 1,628,074. In the said Stanley apparatus a shoulder is not formed in the body prior to the insertion of the 20 bottom, but when the bottom is forced in by a plunger-head, the flanged bottom is caused by the head to expand the body outwardly into a shoulder in the holder. A similar arrangement is shown in other 25 patents. With the present invention however, a shoulder is formed in the body previous to the insertion of the flanged bottom, and facilitates the operation of the machine.

What I claim is:—

30 1. In a machine for forming paper containers with a flanged bottom inserted and secured in one end of a body, the combination with a carrier for the body that is advanced to bring the body to a certain station, means at one station for inserting a bottom in the body and means at an advanced station to secure the bottom in the body end portion, of means at a station in advance of said stations to engage the body 35 before the insertion of the bottom which means is arranged to impart a special shaping to the body end portion adapted to receive the bottom and facilitate the securing of the bottom in the container.

40 2. In a machine for forming paper containers with a flanged bottom inserted and secured in one end of a body, the combination with a carrier for the bodies that is advanced to bring the body to certain stations, means at one station for inserting the bottom in the body and means at an advanced station to secure the bottom in the body end portion, of means at a station in advance of said stations to engage the body 45 before the insertion of the bottom which means is arranged to impart a special shaping to the body end portion to form an inner ledge, adapted to receive the bottom and facilitate the securing of the bottom in the container.

50 3. In a machine for forming paper containers of conical form with a flanged bottom inserted and secured in one end of a body, the combination with a carrier for the body that is advanced to bring the body to certain stations, means at one station for inserting the bottom in the body and means at an advanced station to secure the bottom in the body end portion, of means at a station in advance of said stations to engage the body 55 before the insertion of the bottom which means is arranged to impart a special shaping to the body end portion to form an inner ledge, adapted to receive the bottom and facilitate the securing of the bottom in the container.

60 3. In a machine for forming paper containers of conical form with a flanged bottom inserted and secured in one end of a body, the combination with a carrier for the body that is advanced to bring the body to certain stations, means at one station for inserting the bottom in the body and means at an ad-

certain stations, means at one station for inserting a flanged bottom in the body and means at an advanced station to secure the bottom in the body end portion, of means at a station in advance of said stations to support the conical body before the insertion of the bottom which means will impart a special shaping of the body end portion adapted to receive the bottom flange and facilitates the securing of the bottom in the 70 container.

4. In a machine for forming paper containers of conical form with a flanged bottom inserted and secured on one end of the body, the combination with a carrier for the bodies that is advanced to bring the bodies to a certain station, means at one station for inserting the bottom in the bodies and means at an advanced station to secure the bottom in the body end portion, of means at a station in advance of said stations to engage the conical body end portion before the insertion of the bottom, which means is arranged to impart a special shaping to the body end portion to form an inner ledge 80 adapted to receive the bottom and facilitate the securing of the bottom in the body.

5. In a machine for forming paper containers with a flanged bottom inserted and secured in one end of the body, the combination with a carrier for the bodies that is advanced to bring the bodies to certain stations, means at one station for inserting the bottom in the bodies and means at an advanced station to secure the bottom in the body end portion, of means at a station in advance of said stations to support the body before the insertion of the bottom, which means includes a die arranged to engage the inner wall of the body to press it outwards 90 to form a shoulder in the wall, whereby to engage the inserted bottom.

6. In a machine for forming paper containers of conical form with a flanged bottom inserted and secured in one end of the body, the combination with a carrier for the bodies that is advanced to bring the bodies to certain stations, means at one station for inserting the bottoms in the bodies and means at an advanced station to secure the bottom in the body end portion, of means at a station in advance of said stations to engage the body before the insertion of the bottom, which means includes a die arranged to engage the inner wall of the body 100 to press it outwards to form a shoulder in the body conical wall, whereby to engage the bottom when inserted.

7. In a machine for forming paper containers with a flanged bottom inserted and secured in one end of the body, the combination with a carrier for the bodies that is advanced to bring the body to certain stations, means at one station for inserting the bottom in the bodies and means at an ad-

vanced station to secure the bottom in the body end portion, of means at a station in advance of said stations to engage the body before the insertion of the bottom, which 5 means includes a die arranged to engage the inner wall of the body to press it outwards and make it cylindrical with a shoulder at the connection with the body wall, whereby to engage the end of the flange of the in-
10 serted bottom.

8. In a machine for forming paper containers of conical form with a flanged bottom inserted and secured in one end of the body, the combination with a carrier for the 15 bodies that is advanced to bring the bodies to certain stations, means at one station for inserting the bottoms in the bodies and means at an advanced station to secure the bottom in the body end portion, of means 20 at a station in advance of said stations to engage the body before the insertion of the bottom, which means includes a die arranged to engage the inner wall of the body to press it outwards and make it cylindrical with a 25 shoulder at the connection with the conical body, whereby to engage the end of the bottom flange when inserted.

9. The combination of a holder having a conical bore adapted to receive and hold a 30 conical body of paper that will project beyond the end wall of the holder at the larger end for a short distance, a plunger, a sleeve carried by the plunger that is movable relative to the holder to be brought against the 35 larger end of the holder with the sleeve bore surrounding the projecting end of the body, a head carried by the plunger and movable inside of the said sleeve, which head is smaller than the sleeve bore whereby an annular 40 space is provided between the head and the sleeve adapted to receive the body end portion therebetween, means for advancing the sleeve to inclose the body projecting end until the sleeve engages the holder end wall, 45 and means for thereupon advancing the head into the body to press it outwardly toward the sleeve bore, the head being slightly larger than the holder bore at its outer end, whereby to cause the head to expand the 50 body end portion to form a shoulder in the body end portion between the head and the said end wall of the holder.

10. The combination of a holder having a conical bore adapted to receive and hold a 55 conical body of paper that will project beyond the end wall of the holder at the larger end for a short distance, a plunger, a sleeve carried by the plunger that is movable relative to the holder to be brought 60 against the larger end of the holder with the sleeve bore surrounding the projecting end of the body, a head rigidly carried by the plunger and movable inside of the said 65 sleeve, which head is smaller than the sleeve bore, whereby an annular space is provided

between the head and the sleeve to receive the body end portion therebetween, spring connecting the sleeve with the head, means for advancing the plunger to cause the sleeve to inclose the body projecting end until the sleeve has advanced to engage the holder, and further advance of the plunger will further advance the head into the arrested sleeve and into the body to press the body outwardly toward the sleeve bore, the head being slightly larger than the holder bore at its outer end, whereby to cause the head to expand the body end portion to form a shoulder in the body end portion between the head and the said end wall of the holder. 70
